STOOL

Jose A. Lopez, Miami, Fla., assignor to Camilo Muebles, Inc.

Filed June 13, 1975, Ser. No. 586,717

Term of patent 14 years

Int. Cl. D6—01

U.S. Cl. D6—36

FIG. 1

FIG. 2

FIG. 3

FIG. 4

FIG. 5

FIG. 6

FIG. 7

FIG. 8

FIG. 1 is a front elevational view of a stool showing my design;

FIG. 2 is a left side elevational view thereof;

FIG. 3 is a top plan view thereof;

FIG. 4 is a bottom plan view thereof;

FIG. 5 is a front elevational view of a modified form of the stool shown in FIG. 1;

FIG. 6 is a left side elevational view of the stool in FIG. 5;

FIG. 7 is a top plan view of the stool in FIG. 5; and FIG. 8 is a bottom plan view of the stool in FIG. 5.

I claim:

The ornamental design for a stool, as shown.
